UNITED STATES PATENT OFFICE.

THORNTON L. RICHARDSON, OF WASHINGTON, DISTRICT OF COLUMBIA.

CORD-FASTENING DEVICE.

Application filed April 23, 1924. Serial No. 708,580.

(FILED UNDER THE ACT OF MARCH 3, 1883, 22 STAT. L., 625.)

To all whom it may concern:

Be it known that I, THORNTON L. RICHARDSON, a citizen of the United States, residing at Washington, District of Columbia, have invented certain new and useful Improvements in Cord-Fastening Devices, of which the following is a specification.

The invention described herein may be used by the Government of the United States or any of its officers or employees, or by any other person of the United States in the prosecution of work for the Government without the payment of any royalty thereon.

15 This invention relates to improvements in cord fastening devices.

The present invention is particularly adapted to be employed for securing cords used in drawing together the open end of a mail bag or the like.

Among the objects of the invention is to provide a device of the above character which is durable and inexpensive to manufacture; which will operate to simultaneously secure a plurality of cords, and which will not injure the cords secured thereby.

It is also an object of the invention that the device permit a lock of conventional construction, such as a padlock or the like, to be employed in connection therewith to prevent releasing of the cords held by the fastener and thereby eliminate any possibility of an unauthorized person opening the bag with which the cords are associated.

35 It is further within the scope of the objects of the invention that substantially all the parts constituting the fastening device be of such construction that the same may be stamped from sheet metal and thus reducing the cost of manufacturing the device to a minimum.

The invention is illustrated by way of example in the accompanying drawings, in which—

45 Figure 1 is a top plan view of the device showing the same applied, the cords being shown in dotted lines;

50 Figures 2 and 3 are vertical longitudinal sectional views of the same showing the device with its actuating lever in released position and applied position, respectively, with relation to the cords threaded through the device;

55 Figure 4 is a bottom view of the base plate employed in the construction of the device;

Figure 5 is a view in side elevation of the supporting plate employed;

Figure 6 is a perspective view of the actuating lever;

Figure 7 is a perspective view of a channel clip employed as a guide member, and,

Figure 8 is a perspective view of a housing or cap employed in the construction of the device.

Referring to the drawings more particularly, 10 indicates generally, a base plate which preferably is of the shape shown. This base plate is formed with an inturned flange or lip 11 along each longitudinal edge. These flanges or lips are turned toward the bottom face of the plate, as shown to advantage in Figures 2, 3 and 4. One end of the base plate is provided with a tang 12, and adjacent the last-named end of the plate there is provided a pair of elongated openings or slots 13. Also, the plate has its bottom surface provided with a protrusion 14 preferably of the shape shown. Openings 15, 16 and 17 are provided and arranged centrally and longitudinally of the plate 10. Also, a pair of aligned openings 18 are provided adjacent each longitudinal edge of the plate and near one end thereof, said openings being preferably of the shape shown. It may be here mentioned that the different openings heretofore referred to, together with the protrusion 14, may be made in one or more stamping operations. This is also true with respect to the flanges or lips 11 and the tang 12.

The supporting plate is specifically shown in Figure 5 and generally designated by the reference character 19. This member may be stamped from sheet metal and comprises an elongated plate terminating at one end in the tapering portion 20 and terminating at its other end in a projection 21 which is formed with a laterally-extending tooth or projection 22. The member 19 is shown in its upright position in Figure 5, and as seen, the tooth 22 occurs on the lower edge of the projection 21. The plate is further provided with an opening 23 which is preferably circular. Adjacent the portion 20 of the plate there is formed a recess 24 which is substantially triangular in shape and is made with a view of providing a curved edge portion 26 and a seat or ledge 27. Between the ledge 27 and seat 26 there occurs a curved raised edge portion 28. The plate

19 is also formed with two openings 29 and 30, and upon the lower edge of the plate there is formed two semicircular protrusions 31 and 32.

5 As shown specifically in Figure 6, the actuating lever generally designated by the reference character 33 comprises a plate which is stamped to provide a slightly enlarged curved end portion 34 which terminates in an upwardly curved lip to form what may be termed a heel. The lip 35 is formed with a plate extension 36 which may be referred to as a head. The plate constituting the actuating lever is provided 10 with a centrally and longitudinally extending slot 37 which terminates at its one end in an enlargement 38.

A pin 39 is extended through the opening 30 of plate 19 and this pin is arranged 20 to project from each side of the plate. The pin 39 pivotally supports a pair of dogs 40 upon each side of the plate 19. The dogs 40 are preferably rectangular in shape and each dog has its corners beveled as is shown.

25 A pin 41 is extended through the opening 29 of plate 19 and carries a pair of rollers 42, a roller being arranged upon each side of the plate as shown and the ends of the pin being upset in order to hold the rollers 30 against removal from the pin. The plate 19 and also the plate which constitutes the actuating lever may be stamped from sheet metal and this is also true of the dogs 40.

35 There is further provided a guide member 41, which is specifically shown in Figure 7 and constitutes what may be termed a channel clip, the bridge portion of which is preferably dished as shown. Each side portion of the channel clip is provided with a tooth 42. Also, there is provided a cap or housing 43 which is of the construction shown in Figure 8. This housing is also in the form 40 of a channel member with the side portions thereof substantially triangular in shape. Each side portion has its free edge provided 45 with a pair of teeth 44. Also, one end of the bridge portion of the cap is provided with a slot 45.

In assembling the present device the plate 50 member 19 may be first fixed upon the base plate 10. In positioning and fixing this plate its tooth 22 should be extended through opening 15 of the base plate 10 and the free end of this tooth upset in order to secure the member 19 to the base plate. Also, the protrusions 31 and 32 should be positioned so 55 that they extend into the openings 17 and 16, respectively. Previous to fixing the plate member 19 the actuating lever 33 should be positioned. In positioning the actuating lever the forward end of the plate 19 should be extended through the slot 37 of the lever 33 and the heel 35 of this lever, together with the head 36, brought into the recess 24 as shown to advantage in Figure 2.

It will be assumed that the rollers 42 and the dogs 40 have previously been secured to the supporting plate 19. The cap 43 may now be positioned and as shown in Figures 2 and 3, the bridge portion of this cap should fit upon the upper edge of the plate portion 20. Also, a portion of the upper edge of the plate 19 should extend into the slot 45 of the cap 43. The teeth 44 of the cap 43 should be extended into the opening 18 of the base plate 10 and these teeth may now be upset to rigidly secure the cap to the base plate. The guide member 41 may now be placed in position and in doing this its teeth 42 should be extended through the openings 13 of the base plate 10 and said teeth upset in order to rigidly secure this member to the base plate.

In the use of a cord or rope for securely closing the open end of a mail bag the cord is usually extended through a plurality of eyelets fixed in said bag about the open end thereof. The end portions of the cord should be threaded through the present device. In doing this the end portions of the cord are arranged as shown in Figures 1 and 2—that is, these cords are extended through the cap 43, one upon each side of the supporting plate 19; then extended through the slot enlargement 38 of the actuating lever 33, and then further extended through the guide member 41. The cords are shown in dotted lines in Figures 1, 2 and 3. The actuating lever 33 should have the position illustrated in Figure 2 in order to permit free slipping of the cords through the device, and as seen in this figure, the heel 35 of the actuating lever is in engagement with the curved edge portion 26 of the recess 24. The recess 24 should be sufficiently large to permit rocking movement of the actuating member 33.

When the cords have been arranged as desired, then the actuating lever 33 should be depressed and brought into the position illustrated in Figure 3. It will be noted that the projection 21 serves as a stop to limit downward swinging movement of the lever 33. Through this downward swinging movement of the lever 33 the heel 35 will move over the raised edge portion 28 of recess 24 and eventually seat upon the ledge 27. The rollers 42, as is obvious, will facilitate this movement of the lever 33. The head 36 of lever 33 will swing upwardly and bind the cords about the dogs 40. The dogs 40 normally have the position illustrated in Figure 2 and upon the head 36 of lever 33 swinging upwardly the dogs will move to the position illustrated in Figure 3. The dogs as shown in Figure 3 are substantially vertical—that is, with respect to the longitudinal axes thereof, and as is apparent by this arrangement of the dogs the same more efficiently cooperate with the actuating lever for binding the cords. The cords in reality

are bound tightly about the dogs 40 and are thus held against movement.

If desired, the hasp of a padlock may now be extended through the opening 23 of plate 5 19 and the padlock locked. The padlock prevents lifting of the lever 33.

When it is desired to release the cords held by the device, then the padlock referred to should be removed and the actuating lever 10 33 can be swung to the position illustrated in Figure 2. With the lever in this position the cords may be easily drawn through the device.

While I have shown and described the 15 preferred form of my invention, I wish it to be understood that I am aware of the fact that the construction, combination and general arrangement of parts might be changed by those skilled in the art without departing 20 from the spirit of my invention as indicated by the appending claims.

What I claim is:

1. A cord fastening device comprising an elongated supporting plate along the side 25 of which cords may be arranged, a lever fulcrumed by the supporting plate and means adapted to cooperate with the lever for binding the cords when said lever assumes a predetermined position.

2. A cord fastening device comprising a supporting plate along the sides of which cords may be arranged, a lever fulcrumed by said supporting plate, and means carried by the supporting plate adapted to cooperate 35 with the lever for binding the cords when said lever assumes a predetermined position.

3. A cord fastening device comprising a supporting plate, guide means carried by said supporting plate whereby cords may be held adjacent to the sides of said supporting plate, a lever fulcrumed by the supporting plate and means adapted to cooperate 40 with the lever for binding the cords when said lever assumes a predetermined position.

4. A cord fastening device comprising a supporting plate along the sides of which cords may be arranged, a lever fulcrumed by said supporting plate, and dogs carried upon the sides of the supporting plate 45 adapted to cooperate with the lever for binding the cords when said lever assumes a certain position.

5. A cord fastening device comprising a supporting member along the sides of which cords may be arranged, a lever fulcrumed by said supporting member, and dogs pivotally supported by said supporting member adapted to cooperate with the lever for binding the cords when said lever assumes 50 a certain position.

6. A cord fastening device comprising an elongated supporting plate along the sides of which cords may be arranged, a lever fulcrumed by the supporting plate, said lever having a head at its one end adapted to

move in a recess in said supporting plate and lift the cords when the lever is swung in a proper direction, and means adapted to cooperate with the head of the lever for binding the cords during the last named 70 movement of said lever.

7. A cord fastening device comprising a supporting plate along the sides of which cords may be arranged, a lever fulcrumed by the supporting plate, its one end being 75 adapted to engage beneath the cords and raise the same when said lever is operated, and means carried by the supporting plate adapted to engage the cords and bind the same during the operative movement of said 80 lever.

8. A cord fastening device comprising a supporting member along which cords may be arranged, a lever fulcrumed by the supporting member, its one end being adapted 85 to engage beneath the cords and raise the same when said lever is operated, and pivotally supported dogs carried by the supporting member about which the cords are bound during the operative movement of 90 said lever.

9. A cord fastening device comprising a supporting member along which cords may be arranged, an actuating lever comprising a plate member with a longitudinally extending slot through which the supporting member is extended, said lever being formed at its one end with a heel and a head extending laterally from the heel, said head being adapted to engage beneath the cords, 95 means for supporting the heel to fulcrum the lever, and means whereby with the lever being rocked to swing said head upwardly the cords will be bound.

10. A cord fastening device comprising a supporting member along which cords may be arranged, an actuating lever comprising a plate member with a longitudinally extending slot through which the supporting member is extended, said lever being formed 100 at its one end with a heel and a head extending laterally from the heel, said head being adapted to engage beneath the cords, means for supporting the heel to fulcrum the lever, and dogs carried by said supporting member whereby with the lever being rocked to swing said head upwardly the cords will be bound about said dogs.

11. A cord fastening device comprising a supporting member along which cords may be arranged, an actuating lever comprising a plate member with a longitudinally extending slot through which the supporting member is extended, said lever being formed 115 at its one end with a heel and a head extending laterally from the heel, said head being adapted to engage beneath the cords, means for supporting the heel to fulcrum the lever, dogs carried by said supporting member whereby with the lever being rocked to swing said head upwardly the cords will be bound about said dogs.

- being rocked to swing said head upwardly the cords will be bound about said dogs, and rollers to facilitate the rocking movement of said lever.
12. A cord fastening device comprising a supporting member along which cords may be arranged, a lever comprising a plate with a longitudinally extending slot through which the supporting plate extends, a transversely disposed heel formed at one end of the lever, said heel being disposed in a recess in said plate and adapted to rest upon the edge formed by said recess, a head carried by the heel and disposed beneath the cords and dogs carried by the plate and disposed above the cords whereby with rocking movement of the lever for elevating its head the cords will be bound about said dog.
13. A cord fastening device comprising a supporting member along which cords may be arranged, a lever comprising a plate with a longitudinally extending slot through which the supporting plate extends, a transversely disposed heel formed at one end of the lever, said heel being disposed in a recess in said plate and adapted to rest upon the edge formed by said recess, a head carried by the heel and disposed beneath the cords, and dogs pivotally supported by the plate and disposed above said cords whereby with rocking movement of the lever upon its heel to swing its head upwardly the cords will be bound about the dogs and said dogs moved to a transverse position with respect to the cords for further cooperating with said lever for binding said cords about the dogs.
14. A device of the character described comprising a base plate, a supporting plate extending vertically and longitudinally of the base plate, a lever fulcrumed by said supporting plate, said supporting plate being adapted to permit cords to be arranged along the side thereof and said cords being disposed above the lever whereby with swinging movement of the lever the cords will be raised, and dogs carried by the plate adapted to cooperate with the lever for binding said cords during the period said cords are raised.
15. A device of the character described comprising a base plate, a supporting plate extending vertically and longitudinally of the base plate, a lever fulcrumed by said supporting plate, said supporting plate being adapted to permit cords to be arranged along the side thereof and said cords being disposed above the lever whereby with swinging movement of the lever the cords will be raised, dogs carried by the plate adapted to cooperate with the lever for binding said cords during the period said cords are raised, and means whereby a lock may be employed for securing the lever in position for binding said cords.

THORNTON L. RICHARDSON.
